UNITED STATES PATENT OFFICE.

LUDWIG L. BLAKE, OF SOUTH BEND, INDIANA.

BINDING-STRIP FOR FLOOR-COVERING.

1,317,477.

Specification of Letters Patent. Patented Sept. 30, 1919.

Application filed February 11, 1918. Serial No. 216,592.

To all whom it may concern:

Be it known that I, LUDWIG L. BLAKE, a citizen of the United States, residing at South Bend, in the county of St. Joseph and

5 State of Indiana, have invented certain new and useful Improvements in Binding-Strips for Floor-Covering, of which the following is a specification.

The invention relates to a floor covering 10 made up of slabs or squares of suitable material, particularly linoleum and similar floor covering material, in which each slab is securely bound down at its marginal edges in an effective manner by strips which form 15 the dividing line between adjoining slabs, so that as a whole the same will be imitative of and have the characteristics in appearance of a tile or parquet floor.

The primary object of the invention resides 20 in the provision of uniform metallic binding or securing strips for the edge margins of slabs or squares of linoleum or like floor fabrics, which are of a structure which will not readily bend or yield under the 25 weight of persons walking thereon, and by the use of which strips an artistic and exceedingly serviceable floor covering may be made by the use of linoleum remnants or cuttings which are now mainly wasted or 30 scrapped. A further object resides in so forming the securing strips that a single strip will serve to form a marginal edge binding for two adjoining squares or slabs, and which are of sufficient rigidity through- 35 out their length to prevent distortion there- of by ordinary stresses to which same may be subjected, and by virtue of which rigidity but a single fastening element applied to each end thereof and to the floor proper will 40 suffice to hold the strip in proper relation with respect to the slabs retained thereby.

A still further object resides in providing each end of the strips with a depression, so that the meeting ends of alined strips, as 45 for example, the intersecting ends of four crosswise arranged strips, will jointly form a shallow socket adapted to receive a large headed nail so as not to materially or in no wise protrude above the strips, and the 50 head of which nail will overlap and secure the end of each strip so arranged. A still further object resides in providing the strips with mitered corner edges, so that the extreme 55 ends of four intersecting crosswise arranged strips will be equidistant, and form an opening to permit a nail to be

driven therethrough, and with the head of the nail bearing upon substantially equal parts of the strip ends.

With the above and other objects in view, 60 the invention will be described in the following specification, reference being had particularly to the accompanying drawings, in which:

Figure 1 is a plan view illustrating the 65 application of the invention.

Fig. 2 is an enlarged fragmentary sectional view taken on the line 2—2 of Fig. 1.

Fig. 3 is a fragmentary plan view showing the corners of four adjoining slabs and 70 the manner of securing same.

Fig. 4 is a perspective view of one end of a securing strip.

Fig. 5 is a view in elevation showing the proximate ends of alined securing strips and 75 the fastening element therefor.

Referring now more particularly to the accompanying drawings, the reference numeral 5 indicates slabs or squares which may consist of any suitable material usable as a 80 floor covering, such as linoleum and the like, and preferably rectangular in form. The slabs are preferably arranged upon the floor to be covered in uniform parallel rows and in relatively slightly spaced relation, with 85 the spaces between the rows in alinement.

In order to hold the slabs in proper relative position and fixed with relation to the floor to be covered, as well as to provide a protection or binding for the marginal 90 edge of each slab, I provide metallic strips 6, preferably and approximately of a length corresponding to the edge length of the slabs, and substantially T-form in cross section, the web portions 7 of which are disposed between the spaces formed by adjoining slabs, the spacing of which is such as to afford a snug fit for the web. The head portion 8 of the strip, which extends at right angles to both sides of the web, is thus 95 adapted to overlie the marginal edges of two adjoining slabs, as shown in Fig. 2. The T-shaped formation of the strip in cross-section gives the same rigidity, so that the same will not easily yield or flex under 100 the weight of a person stepping thereon. To further guard against the strips yielding or bending under weight applied thereon, the web portions thereof are of a height substantially equal to the thickness of the slabs, 105 so that in applied position the web will rest throughout its length upon the floor proper. 110

Such rigidity of structure further permits the strips to be secured or fastened to the floor proper in an effective manner by fastening elements applied to the ends thereof only, and without effecting any bulge or upward bend in the strip intermediate its ends, so that the strip heads will have contact with the slabs throughout their length.

The preferred manner of forming the strips, consists in folding a sheet metal strip upon itself along its longitudinal center to form the web portion 7, and thence bending the longitudinal margins thereof in opposite directions and at substantially right angles 15 to the web to form the head portion 8, the strip thus having a substantially T-form in cross section. The head end portions are depressed, as at 9, so that the head end of nail, as 10, will not protrude above the 20 surface plane of the strip in securing the same to the floor by driving the nail thereinto. Fig. 5 illustrates how the head of the nail fits or is seated in the socket formed by the meeting ends of aligned strips, one nail 25 securing two ends of separate strips, and Fig. 3 illustrates how a single nail serves to secure four ends of separate strips. The ends of the strip heads are also partially mitered, as at 11, so that the ends of four 30 intersecting strips, as shown in Fig. 3, will be relatively equidistant, thus forming an opening between the ends, and at the same time permit the head of the nail to bear upon substantially equal parts of the strips.

35 It will be apparent from the foregoing

that, by the use of the described securing strips and slabs or squares of linoleum or similar floor fabrics, for which the cuttings or remnants of such fabrics may be used, a very serviceable as well as artistic floor covering may be provided.

Having thus described my invention, what is claimed is:

1. A securing strip for floor slabs consisting of a metallic blank longitudinally folded upon itself to provide a relatively thin and rigid upstanding web portion, and oppositely bent lateral edge margins to provide a head portion, the strip being substantially of T-form in cross section. 45

2. A securing strip for floor slabs consisting of a metallic blank longitudinally folded to provide a relatively thin and rigid upstanding web portion, and edge margins oppositely bent at substantially right angles 50 to the web portion and depressed at their ends, the strip being of substantially T-form in cross section.

3. A securing strip for floor slabs consisting of a metallic blank longitudinally folded to provide a relatively thin and rigid upstanding web portion, and edge margins oppositely bent at substantially right angles 55 to the web portion, the said margins being depressed at their ends and their corners mitered, the strip throughout its length being of substantially T-form in cross section. 60

In testimony whereof I affix my signature.

LUDWIG L. BLAKE.
